US0D1105028S

(12) **United States Design Patent** (10) **Patent No.:** **US D1,105,028 S**
(45) **Date of Patent:** **** Dec. 9, 2025**

(54) **MEDIA PLAYER DEVICE**

(71) Applicant: **Sonos, Inc.**, Santa Barbara, CA (US)

(72) Inventors: **Aki Laine**, Santa Barbara, CA (US);
Philippe Vossel, Wuppertal (DE);
Edward Mitchell, Thousand Oaks, CA (US)

(73) Assignee: **SONOS, INC.**, Goleta, CA (US)

(**) Term: **15 Years**

(21) Appl. No.: **29/873,558**

(22) Filed: **Apr. 3, 2023**

Related U.S. Application Data

(63) Continuation of application No. 29/764,312, filed on Dec. 29, 2020, now Pat. No. Des. 982,546, which is a continuation of application No. 29/661,007, filed on Aug. 23, 2018, now Pat. No. Des. 910,590.

(57) **CLAIM**

The ornamental design for a media player device as shown and described.

DESCRIPTION

FIG. 1 is a front elevation view of a media player device, according to our new design.

FIG. 2 is rear elevation view.

FIG. 3 is a first side elevation view.

FIG. 4 is a second side view.

FIG. 5 is a top plan view.

FIG. 6 is a bottom plan view.

FIG. 7 is a first perspective view; and,

FIG. 8 is a second perspective view.

The broken lines depict portions of the article that form no part of the claimed design.

1 Claim, 6 Drawing Sheets
